MACHINE FOR PRODUCING JUSTIFIED
LINES OF PRINTING TYPES

Julius Schneider, Munich, Germany

Application July 10, 1935, Serial No. 30,651. In
Germany September 25, 1933

2 Claims. (Cl. 199—80)

It has already been proposed to construct machines for producing justified lines of printers' types, the types being first assembled word by word and the words being then inserted one by one into the composing galley, with interposition of spacing blocks which have first been cast, of the correct width. In a known machine of this kind the required width of the spacing blocks is ascertained by reading on a scale the difference between the number of units in the desired length of line and sum of the widths of all the types set, the difference being divided by the number of word spaces. The blocks are then cast by operating a selected space key, according to the required width.

For simplifying the process it has been proposed to adjust the mould automatically according to the required spaces, the machine having a matrix wheel continually rotating in front of a mould of variable size, but the line must be made up with dummies prior to the casting of the types and space blocks, the width of the spaces being ascertained with the aid of the dummies, which are then utilized for adjusting the mould and the matrix wheel above the form.

This arrangement requires the stocking of dummies, and the setting up of the dummy line is a separate operation, prior to the casting proper.

My invention enables the use of dummies to be dispensed with. The matrix wheel rotating in front of the variable size mould and stopped for each casting operation is, according to the invention, directly and positively adjusted for the casting of the types, by a feeler action which is in itself well known, so that the wheel is centred, in accordance with the widths of the types, and for casting the spacing blocks the wheel is stopped, in a manner which is also in itself known by a device which divides the amount of justification required by the number of spaces occurring in the line.

In the accompanying drawings a machine constructed according to the invention is illustrated by way of example.

Fig. 1 is a perspective view of the machine, and Fig. 1a shows part of the same to a larger scale;

Fig. 1b shows a detail in vertical section; Figs. 2 and 3 show details in perspective view. Mounted on a shaft 1 is a wheel 2 secured to the shaft by a spring catch, so that it can be easily removed from the shaft. In the wheel there are two sets of type matrices, side by side, but only one matrix 3 belonging to one of the sets is shown

in Fig. 1. The other matrices are omitted for clearness. The matrices are radially slidable and are normally pulled inwards by springs 4. In addition to the type matrices 3 the wheel has in each set a blank matrix 5, exactly like the matrices 3 except that it has no matrix face. Behind the wheel 2 there are two gears 6 and 7, one for each set of matrices. These gears have tooth gaps corresponding in number to the number of matrices in the respective set. The tooth gaps are of different depths, according to the widths of the types to which they belong. In addition each gear has a deep gap 8, which corresponds to the blank matrix 5. The tooth gaps coact with a feeler 9 for positioning the wheel.

The matrix wheel 2 is axially slidable on the shaft 1, so that either of the two matrix sets can be brought into operative position, as desired. This enables the machine to be used for producing two different styles of type alternatively. If desired more than two matrix sets may be provided on the wheel 2. The feeler 9 coacts with one or the other of the gears 6 or 7, according to the position of the wheel 2.

In the machine there is a mould 10 having connected to its underside the spout 11 of a casting ladle 12. Between the mould and a galley 13 there is a type carrier, in the form of a rotatable drum 14 with magazines formed by axial slots 15. The drum is rotated with the aid of a feed mechanism 16 operated by a key 17, the movement imparted by each depression of the key being such that the magazines 18 are by successive movements placed in alignment with a feed channel 19, which is of the same size as the magazines.

The drum is rotated against the action of a restraining force which tends to rotate it backwards, but backward rotation is prevented by a spring pressed pawl 20. Connection between the magazine 18 in line with the feed channel 19 and the composing galley 13 is afforded by a bridge 21. As long as the magazine is not required to be emptied the bridge is slightly offset with respect to the opposite magazine, thereby forming an abutment which prevents types introduced into the magazine on one side from being ejected therefrom on the other side. Obviously, this abutment may, if desired, be constructed in some other manner and may be positively controlled so as to clear the way at the appropriate moment.

The mould 10, Fig. 1a, is bounded by walls 22, 23, 24, and 25. In the mould wall 24 there is a slide 26 which exposes the mould cavity 10 in the position shown in full lines and serves to

push the cast type or space block in the direction of the feed channel 19 when moved into the position shown in full lines in Fig. 1. The slide 26 is integral with the mould wall 22. In the position shown in Fig. 1a the wall 22 locks an ejector 27 slidable in the channel 19, the ejector being subject to the action of a spring 27a which acts in the direction of the arrow 28. In the position shown in full lines in Fig. 1 the mould wall 22 allows the ejector 27 to move in the direction of the arrow 28. The movable members 22 and 26 of the mould are controlled in opposition to a return force by an abutment 29 rigidly connected to the members 22 and 26. The mould walls 23 and 24 are stationary, but the mould wall 25 is rigidly connected to an axially slidable rod 30 which passes through the members 23, 24 and 26. The rod 30 is connected by means of a pin 31 to the carrier 32 of the feeler 9, so that it is rigidly attached both to the carrier and the feeler.

The wheel 2 is driven by a worm 33 on a shaft 34, the worm being engaged with a worm wheel 35 rotatably mounted on the shaft 1 and is connected thereto by a friction clutch 36. The clutch consists of a spider fixed to the shaft 1, with springy arms bearing against one face of the worm wheel 35. Owing to this arrangement the shaft 1 and the wheel 2 can be stopped while the worm wheel 35 continues its rotation. The shaft 1 is connected by bevel gears 37 and 38 to a hollow shaft 39. The free end of this hollow shaft carries a stop plate 40 which rotates above a circular series of abutments 41 corresponding in number to the number of matrices, including the blank matrix. The abutments are rods slideable in a cylinder 42 so that they can be moved into the path of the plate 40 with the aid of keys 43. For clearness only one key 43 and one abutment 41 is shown in Fig. 1. The number of keys and abutments corresponds to the number of characters or, if a shift key arrangement is provided, to half the number of characters. One key and one abutment are provided for the blank matrix, for casting space blocks.

The plate 40 has an arcuate groove 44 which is closed at the rear by a wall 45. Into the groove extends the chamfered head 46 of a bolt 48 subject to the action of a spring 47. The rear end 50 of the bolt has a cam surface 49 which cooperates with a push rod 50 slidable in the hollow shaft 39. The upper end of the push rod, which projects from the shaft 39, is in engagement with a lever 52 pivoted at 51. Connected to the lever 55 52 by a rod 53 is a locking lever 54 rotatable on a shaft 55. In the position shown in Fig. 2 one edge of the locking member 54, which has a notch 56, engages a stud 57 on a horizontal bolt 58 slidable in the bore of a cylinder 59. The bolt 60 58 is subject to the action of a spring 60 which urges it in the direction of the arrow 61 (Fig. 1). The cylinder 59 is fixed to a shaft 62 carrying a worm wheel 63, meshing with the worm 33, and a cam 64, which is keyed to the shaft, whereas 65 the worm wheel 63 is rotatable on it. The face of the worm wheel has holes 65 into any of which the bolt 58 can be thrust by the action of the spring 60, when released by the locking member 54. The cam 64 cooperates with the free end 66 of a hammer 68 pivoted on a shaft 67, the head of the hammer extending into the wheel 2 so that it can strike whichever matrix is 70 in operative position when the wheel 2 stops. Upon the shaft 62 there are cams 69, 70 and 71, 75 which are omitted for clearness in Fig. 2. The

cam 69 co-operates with the plunger 12 of a casting pump, and the cam 70 acts through one arm of the bell crank lever 73 upon the abutment 29 of the two slidable mould members 22, 26. The cam 71 is double acting, and controls, on the one hand, through a push bar 74, the carrier 32 of the feeler 9, its periphery and, on the other hand it acts by means of an axial extension 75 and follower 76 on a double lever 77 having pivotal points 78 and 79. At the free end of the double lever 77 there is a pin 80 engaging into a groove 81 in a clutch member 82, which is slidable but not rotatable on a shaft 83. This shaft is driven by helical gears 84, 85, from the main drive shaft 34. The gear 85 is connected to the shaft 83 in the same manner as the worm wheel 35 is connected to the shaft 1. The clutch member 82 has dogs, its counterpart being a gear 86 loose on the shaft 83 and having corresponding dogs. The gear 86 is in mesh with a rack 20 87 formed on the lower edge of the ejector 27.

Mounted loosely on an arm 88 of the carrier 32 of the feeler 9 there is a meter abutment 89, which adds up the movements of the feeler. The meter abutment is mounted on free wheel rollers 90 disposed in wedge shaped recesses 91, so that in the course of each return movement of the carrier 32 and feeler 9 in the direction of the arrow 92 the meter abutment 89 is advanced by a corresponding amount, without partaking in movements of the carrier 32 and feeler 9 in the opposite direction. The movement of the meter abutment 89 in the direction of the arrow 92 is therefore in each case dependent on the width of the character which corresponds to the tooth gap of the gear 6 or 7 engaged with the feeler. Owing to the fact that the meter abutment does not partake in the return movements of the carrier the amounts are added up. The meter abutment 89 is loaded by a spring (not shown), which tends to move it in the direction opposite to that of the arrow 92, this tendency of the spring being frustrated by free wheel rollers 93 in a block 94. The block 94 is vertically slideable, so that the rollers 93 can be rendered inoperative by lifting the block. The arm 88 carries an abutment 95 with an inclined face 96. This abutment co-operates with a similarly formed abutment 97, the face 98 of which is parallel with the face 96. The abutment 97 is carried by a weighted beam 99, which can be lifted, as indicated by an arrow 101, by means of a key 100, and is locked in the raised position by a locking member 102. A spring pressed pin or detent 102' is mounted in the member 102 and engages an opening 100' in the key 100, when the latter is depressed (see Fig. 1b). On the shaft of the key 100 there is a key 103, controlling an abutment 104 indicating the completion of the line. This abutment first has the position shown in Fig. 1. It moves in a guide 105 and can be raised with the aid of the key 103 into the operative position shown in dotted lines. In this position it is locked by a spring pressed catch 106. The distance 107 between the abutment 104 and the abutment 98, when the same is in its end position after the formation of all the words of a line, is the difference between the required length of line and the sum of the lengths of all the words on the line. Into the space between the two abutments 98 and 104, while the latter is still in its full line position, a wedge 108 is inserted after the completion of each word, so that after the setting of the last word there are as many wedges between the abut- 75

ments as there are word spaces in the line. The wedge to be inserted is taken from a wedge stock 109. The insertion of the wedges is effected by positive action in accordance with the feed of the magazine drum 14. For this purpose a lever 111 is mounted on the shaft 110 of the feed key 17, and said lever has pivoted thereto a finger 112 engaging the foremost portion of the stock 109. The wedges have elongated holes 113 whereby they are threaded on an inclined rod 115, so that when by depression of the key 17 the finger 112 releases the foremost wedge that wedge slides down the rod 115 and comes to rest against the meter abutment (see-wedge 108), or 15 joins the wedges already inserted. Obviously, provision must be made to assure that only one wedge is released at a time, as is well known in connection with matrix type setting and line casting machines, where one matrix is released at a 20 time.

The machine described operates in the following manner:—

At the beginning of the production of a line the drum 14 has its magazine slot 18 in line with 25 the feed channel 19. The bridge 21 assumes the dotted position and thereby prevents the types introduced into the magazine 18 from being ejected on the opposite side. The mould 10 is closed, i. e. the mould members 22 and 26 occupy 30 the full line position of Fig. 1a. As long as no key is depressed, the worm 33 rotates the shaft 1 and therewith the wheel 2, the locking plate 40 being also rotated. The shaft 83 and the worm wheel 63 also rotate, but not the shaft 62, 35 since this is not coupled to the worm wheel 63. A key 43 is then depressed, corresponding to the first letter of the first word. This moves the corresponding abutment 41 into the path of the plate 40. When the groove 44 engages the 40 projecting abutment 41 the latter strikes the chamfered head 46 of the bolt 47, and pushes the bolt inwards. When the abutment has cleared the bolt it strikes the end wall 45 of the groove and stops the plate 40, shaft 39, bevel gears 38, 45 37, shaft 1 and wheel 2. In this position the matrix 3 which corresponds to the depressed key 43 faces the mould 10. The worm wheel 35 continues its rotation, its side face rubbing against the springy arms 36 of the friction clutch. When 50 the abutment 41 has cleared the head 46 of the bolt 47 the latter returns to its normal position, but its rearward movement causes the cam surface 49 to lift the push rod 50 and rock the lever 52 so that the locking lever 54 is lifted 55 and releases the stud 57. The lever 54 is lifted only for an instant, but this is sufficient to cause the bolt 58 to be thrust by the spring 60 into one of the holes 65 in the worm wheel 63. The shaft 62 is thus coupled with the worm wheel 63 and 60 connected to the worm 33, so that the shaft 62 rotates until the stud 57 of the bolt 58 is pulled back by engagement with an inclined portion of the edge of the notch in the locking lever 54. The shaft 62 has then made a complete revolution. By 65 this means the cams 64, 69, 70 and 71 are actuated. First the cam 71 releases the push rod 74 and the carrier 32 of the feeler 9, so that a spring (not shown) causes the feeler 9 to engage the tooth gap of the gear 6 which corresponds 70 to the depressed key. The wheel 2 is thus locked in a position in which the matrix 3 is accurately positioned above the mould 10. Since the rod 30 is rigidly connected to the carrier 32 of the feeler 9 it performs exactly the same movement 75 as the feeler 9, thereby determining the width

of the mould, i. e. the deeper the tooth gap which the feeler has engaged the larger is the width of the mould. Since the depth of each gap corresponds to the width of the character to which it belongs, the width of the mould in each case equals the width of the type to be cast.

Following the adjustment of the mould 10 the cam 64 becomes operative, engaging the lever arm 66 of the hammer 68 and causing the hammer to drive the matrix 3 towards the open mouth 10 of the mould 10. The casting operation is performed by the cam 69, which engages the plunger rod 72 of the casting pump, thereby causing the type metal to be injected into the mould through the casting spout 11. Following this 15 operation, but with such interval as allows the type metal to set, the cam 70 engages one arm of the bell crank lever 73 and causes the other arm and the abutment 29 to move the parts 22 and 26 of the mould in the direction of the arrow 20 116, against the action of a spring not shown. The members 22 and 26 are thus moved from the dotted position of Fig. 1 into the full line position, and the slide 26 moves the cast type with 25 it towards the delivery channel 19. The mould member 22 releases the ejector 27, so that same shoots forward under the action of a spring, in the direction of the arrow 28, and pushes the cast type into the magazine, which is in the receiving position, this magazine being distinguished 30 by the reference numeral 18 from the others marked 15. The type is advanced until it abuts against the bridge 21. Then the part 75 of the cam 71 engages the follower 76 of the double lever 77, and the latter causes the clutch member 35 82 to engage the clutch gear 86, which is loose on the shaft 83, so that the gear 86 is actuated by the shaft 83 and by virtue of its engagement with the toothed lower edge 87 of the ejector 27 causes same to return to its initial 40 position, against the action of its spring. The period of engagement of the members 82 and 86 is sufficient to enable the ejector 27 to return to its initial position. Shortly before the release of the pin 76 the cam 70 also releases the bell 45 crank lever 73, so that first of all the members 22 and 26 of the mould return to the dotted position of Fig. 1, and then the lever 77 returns to its initial position, thereby throwing the clutch members 82 and 86 out of engagement. 50 The ejector 27 is then again locked by the mould member 22.

On completion of the revolution of the shaft 62 the cam 71 engages the push bar 74 and moves the carrier 32 and the feeler 9 and mould rod 55 30 into the initial position. The amount of the return movement depends on the depth of the tooth gap from which the feeler is being withdrawn. The meter abutment 89 connected to the arm 88 of the carrier 32 travels a corresponding 60 amount. Therefore, the travel of the meter abutment also corresponds to the depth of the tooth gap from which the feeler is withdrawn, and is thus proportional to the width of the cast type. 65

The above described process is repeated in exactly the same manner during the casting of each following type for forming the first word on the line, but of course with the proper letter keys depressed. After each casting the meter abutment 70 89 moves by an amount which corresponds to the depth of the tooth gap from which the feeler 9 is withdrawn. These amounts of travel are added up by the meter abutment 89, since the meter abutment is unable to follow the move- 75

ments of the carrier in a direction opposite to that of the arrow 92.

When all the types for the first word of the line have thus been collected in the magazine 18 the key 17 is depressed, and thereby the drum is advanced until the next magazine 15 is in line with the delivery channel 19. The movement of the key 17 is transmitted to the finger 112, so that this releases the first wedge of the wedge stock 109. This wedge slides down the inclined rod 15 to the meter abutment 89. This process is continued until all the words of the line have been set and each word has been introduced into a magazine of the drum 14.

Obviously, the meter abutment 89 operates in the aforesaid manner for each word, so that after the casting of the last word the aggregate travel of the meter abutment 89 corresponds to the sum of the widths of all the types on the line. At each depression of the key 17 a further wedge from the wedge stock 109 is added, the total number of wedges being equal to the number of the word spaces on the line.

When the last type has been cast and pushed into the appropriate magazine the key 20 is depressed and this causes the magazine drum to return under the action of a return force into the position in which the magazine charged with the types of the first word of the line is in alignment with the delivery channel 19. Now follows the justification necessary for obtaining the desired length of line. For this purpose the key 103 is depressed, so that the abutment 104 is raised into the dotted position, being locked in such position by the locking member 106. Between the meter abutment 89 and the abutment 104 there are the wedges which have been released one by one by the finger 112 at each depression of the key 17 and have slid down along the rod 115. These wedges are shown in dotted lines in Fig. 1. By depression of the key 100 the weight beam 99 is raised in the direction of the arrow 101, the wedges being thereby forced between the abutments 89 and 104. As the distance apart of the abutments 89 and 104 corresponds to the required length of line and since moreover the number of wedges forced between the said abutments corresponds to the number of word spaces, the distance travelled by the beam 99 corresponds to the spacing required for obtaining the correct length of line. This travel is therefore utilized for adjusting the mould member 25 in such manner that the spaces now to be cast have the correct width. The abutment 97 on the weight beam 99 is in the path of the abutment 95 on the arm 88 of the carrier 32 when the weight beam is raised, and the higher the weight beam 99 is raised, when the set of wedges is forced between the abutments 89 and 104, the sooner does the abutment 95 strike the abutment 97 when the carrier 32 is moved in opposition to the arrow 92. The distance through which the abutment 95 travels before it strikes the abutment 97 is therefore a measure of the width of the spacing blocks to be cast.

The spaces are cast, as already explained, in the mould 10 in exactly the same manner as the types are cast. The key 43 corresponding to the blank matrix 5 is depressed, whereby the blank matrix is caused to move into its operative position opposite the mould 10. As distinct from the procedure followed when the types are cast, the adjustable wall of the mould is not adjusted in accordance with the distance travelled by the 75 feeler 9, but in accordance with the distance trav-

elled by the carrier 32 which is connected to the rod 30 until the abutment 95 strikes the abutment 97. In order that the feeler 9 does not prevent this travel by abutting against the gear 6, there is in this position of the wheel 2 a tooth gap 8 so deep, facing the feeler 9, that the same will meet with no obstacle even when the abutments 95 and 97 are at the largest possible distance apart.

Exactly as described in connection with the casting of the types, the blank matrix is pressed upon the mould by the hammer 68 after the mould member 25 has been adjusted. The form is filled with metal, the set casting is pushed by the slide 26 into the delivery channel 19 and moved by the ejector 27 into the magazine 18 of the first word. Meanwhile the bridge 21 has been moved into the full line position by any suitable actuating mechanism, so that now the ejector 27 not only moves the cast space block into the magazine 18 and causes same to join the last type of the first word, but pushes same together with the block over the bridge 21 into the composing galley 13. When this is accomplished and all parts of the casting mechanism have, as already described, returned to the initial position, the magazine drum 14 is again advanced by the depression of the key 17, until the next magazine is positioned in alignment with the delivery channel 19 and the bridge 21. Thereupon the next space block, of the same size, is cast for the second word, and is caused to join the word in the appropriate magazine and ejected together with same. This procedure is repeated until all the words of the line have been removed from their magazines and the finished line is in position for reading in the composing galley 13.

When the line is completed the wedges 108 must be returned to the position 109, likewise the meter abutment 89 must be pushed back, this being effected upon lifting the block 94. Finally, the weight beam 99 must be returned by releasing the lock 102 and the abutment 104 must be returned by releasing the lock 106. All these return movements may, of course, be brought about by positive operation, but this is not illustrated, for the sake of clearness.

In the form of construction herein described and illustrated mechanical control means are exclusively employed, but these may be replaced by electrical, pneumatic or hydraulic control means.

What I claim as my invention and desire to secure by Letters Patent of the United States is:—

1. In a machine for producing justified lines of printing type, a casting mold of adjustable width, a rotatable matrix wheel adjacent to the mold, a movable feeler cooperating with said wheel, means controlled by movements of the feeler for adjusting the width of the mold to correspond with the particular type which is to be cast, means for separately storing the words of a line as they are cast, means for dividing the amount of necessary justification by the number of word spaces and adjusting the width of the mold accordingly for casting space blocks of proper width, and means for finally assembling the stored words in the form of a line with the cast space blocks between them.

2. In a machine for producing justified lines of printing type, a casting mold of adjustable width, a rotatable wheel adjacent to the mold and carrying a plurality of matrices of different width, a plurality of abutments supported by said

wheel, each of said abutments being coordinated to one of said matrices, a movable feeler co-operating with said abutments, means controlled by movements of the feeler for adjusting the width of the mold to correspond with the particular type which is to be cast, means for separately storing the words of a line as they are cast, means for dividing the amount of necessary

justification by the number of word spaces and adjusting the width of the mold accordingly for casting space blocks of proper width, and means for finally assembling the stored words in the form of a line with the cast space blocks between them. 5

JULIUS SCHNEIDER.
